UNITED STATES PATENT OFFICE.

HIRAM W. RANSOM, OF CINCINNATI, OHIO, ASSIGNOR OF ONE-HALF TO
THE EMERSON & FISHER COMPANY, OF SAME PLACE.

FORGE.

SPECIFICATION forming part of Letters Patent No. 326,588, dated September 22, 1885.

Application filed October 4, 1884. (No model.)

To all whom it may concern:

Be it known that I, HIRAM W. RANSOM, of the city of Cincinnati, in the county of Hamilton and State of Ohio, have invented certain 5 new and useful Improvements in Blacksmith-Forges, of which the following is a specification.

The object of my invention is to provide a cheap, simple, and compact and very durable 10 forge, by the aid of which all kinds of blacksmithing can be done conveniently, and which shall save fuel and produce a very uniform and strong heat.

The several features of my invention and 15 their use, conjointly or otherwise, will be fully apparent from the following description and claims.

In the accompanying drawings, Figure 1 represents a top view of a forge illustrating 20 my invention, part of the lining in the fire-chamber being removed to show the tuyere-plate and my improved mode of constructing it to receive the lining. Fig. 2 is a transverse vertical section taken at the line $x-x$ of Fig. 1. 25 Fig. 3 is an enlarged transverse cross-section through the fire-box and tuyere and connections, taken at the line $y-y$ of Fig. 1. Fig. 4 is a view of the rear or outside of one of the lining-plates for the fire-chamber.

30 A represents a forge-plate of suitable size, on which the iron to be heated, and fuel for the fire, and tools for use are usually to be placed. This plate has its edges C turned up, and is suitably mounted or supported, preferably upon legs, as a , one of such legs being bolted or otherwise secured at each corner of the plate by the bolt-and-nut connection a' . These legs are preferably fastened by any efficient means to the floor or place where the 40 forge is to be used. At any suitable portion of this plate A, preferably near one of the corners, is located the fire-chamber or box A'. This fire-chamber begins at or about in a plane with the top of the said forge-plate or table A, and extends downward. This chamber has walls a^2 , preferably four in number, which taper down toward the plate B'. Each one of these walls a^2 is provided with and covered by a lining, a^3 . The outer or rear surface of

the lining a^3 may be everywhere in contact 50 with the adjacent wall a^2 of the furnace. When the lining assumes the preferred form—viz., of a metallic plate—this plate is preferably separated from the wall a^2 of the furnace-chamber by an interspace, and the latter may be 55 filled with brick, clay, asbestos, or some other suitable material which is to some extent a non-conductor of heat. Ordinarily this interspace is preferably left unfilled, and the air present therein and circulating operates to 60 keep the lining-plate cool and prevent the latter from warping. The presence of this interspace enables the linings to be more conveniently removed and replaced or renewed. Where there is an interspace between the 65 lining and wall a^2 , a convenient mode of keeping the lining from the wall consists in providing the lining with ribs or projections a' , which latter rest against the sides or walls of the fire-chamber and support their respective 70 linings. This makes a fire-chamber that retains the heat, saves fuel, and heats the iron quickly and thoroughly.

B represents the tuyere, which is situated below the fire-chamber A', with its mouth b 75 opening into the bottom of said fire-chamber. Through this tuyere the blast enters the fire-chamber A'. The tuyere-plate B' consists of the bottom portion, b' , and the raised portion b^2 . Through the part b' of this plate and the bottom 80 portion, b^3 , of the fire-chamber pass bolts b^4 , which receive nuts b^5 on their lower ends, and thus tightly hold the tuyere to the fire-chamber.

The peculiar construction of the tuyere-plate B' answers two objects, viz: first, its 85 wings or parts b' form a convenient means for connecting the tuyere to the fire-chamber; second, the part b^2 of the plate being raised somewhat above the part b' , the latter forms a convenient seat for the lining-plate a^3 , while 90 the side or vertical face of the part b^2 forms a shoulder, against which latter receives the side of the lower portions of the lining, and assists in retaining the said linings in position.

The tuyere is preferably furnished with a 95 suitable device for shaking down the ashes. A desirable form of such device is the following well-known one, viz: Within the tuyere,

and just below the contracted portion thereof, is the short bar or knocker D. This bar or knocker is usually triangular in shape, with its corners slightly dull and rounded, and is so situated in the tuyere as that its corners d extend a slight distance up into the contracted neck or mouth of the tuyere and strike the cinders or ashes in the bottom of the fire-chamber A', and allow said ashes or cinders to pass between this short bar or knocker D and the sides of the tuyere and fall onto the sliding door D', when the said short bar or knocker D is revolved or turned by the operator by suitable means, preferably by the handle D², which latter extends out to the edge of the forge, so that it can be easily reached by the operator and turned by him when necessary. This bar or knocker D is rigidly attached on the end of the long arm d³ of this handle D², and the long arm d³ of this handle is journaled at d' d' in the sides C C' of the tuyere.

A suitable device for dropping the ashes may be employed, and the following well-known device is shown in connection with the forge: A sliding door, D', covers the bottom of the tuyere, and having upon its under side two ribs, e e. The sliding door D' has secured to it, at e', the pull-handle E, by means of which the door D' is slid forward or backward, and when pulled forward the ashes which are lying on it drop to the floor or into a receptacle placed under the forge.

A guide-bar, E', is secured at the bottom of the tuyere below the sliding door D'. One end of the guide-bar E' is suitably secured to the side C' of the tuyere, and, running along under the door D', forms a guide upon which the door D', by means of the ribs e e, slides. The guide-bar also has the hook or projection E², which contains at e³ a hole, through which the pull-handle E passes, and forms a guide and support for said handle E. The upper or free end of this guide hook or projection E² is secured, at n, to the side C of the tuyere.

A pipe, F, leads from a bellows or other suitable air-supply to the tuyere B. The air passing into the tuyere through this pipe may be regulated, as is usual in such instances, by a valve or other suitable device placed at any convenient point. The air passing through the pipe F, after the valve has been opened, rushes into the tuyere B and creates a blast, which passes up and out of the tuyere, and strikes the burning fuel in the fire-chamber A'. When the ashes have accumulated in the fire-chamber A', the handle D² is turned, and the bar or knocker D strikes the ashes and they descend, and, after passing said bar, fall upon the sliding door D'. The operator then pulls the handle E, and the ashes are precipitated upon the floor or ground. The pressure of the bar D in the tuyere also regulates the blast.

The entire forge is usually and preferably constructed of iron, but may be made of any other suitable material. The forge-plate A

and the fire-box A' are preferably cast in one piece. The tuyere B and its plate B' and pipe F are preferably made in one piece.

The upright portion b² of the tuyere and the ledge b' of the same afford a secure foothold for the lining, whether same be of brick, clay, &c., or a metal plate, or both metal and clay, brick, asbestos, &c. The upright portion or extension b² of said tuyere also takes the fierce heat of the furnace, and prevents the lower portions of the tuyere from warping or burning out.

While the various features of my invention are preferably used together, one or more of said features may be used without the remainder, and one or more of said features may, so far as applicable, be employed in connection with forges other than the one herein specifically set forth.

What I claim as new, and desire to secure by Letters Patent, is—

1. In a forge, the combination of the forge-plate A and fire-chamber A' and the lining a³, substantially as and for the purposes specified.

2. In a forge, the combination of a forge-plate, A, and the fire-chamber A', made in one piece, and the lining a³ in the fire-chamber, substantially as and for the purposes specified.

3. In a forge, the combination of the tuyere B and the forge-plate A and fire-chamber A' and the lining a³, substantially as and for the purposes specified.

4. In a forge, the forge-plate A and fire-chamber A', having sides a², and the lining a³, having ribs a⁴, substantially as and for the purposes specified.

5. The combination of the tuyere B, tuyere-plate B', consisting of ledge b' and raised portion b², and the forge-plate A and fire-box A', substantially as and for the purposes specified.

6. The combination of the lining a³ and tuyere-plate B', consisting of ledge b' and raised portion b², substantially as and for the purposes specified.

7. The combination of the plate A and fire-box A' and lining a³ and tuyere B and bar or knocker D, with handle D², and door D', with handle E, and the pipe F and legs a, substantially as and for the purposes specified.

8. The tuyere B, having wings b', which are bolted to the portion b³ of the fire-chamber, substantially as and for the purposes specified.

9. The tuyere B, whose plate B' consists of the ledge b' and raised portion b², substantially as and for the purposes specified.

10. The tuyere B, located at the lower portion of the fire-chamber, and provided with raised portion b² and ledge b', in combination with a lining, a³, resting on said ledge, substantially as and for the purposes specified.

11. The tuyere B, located at the lower por-

tion of the fire-chamber, and provided with raised portion b^2 and ledge b' , in combination with a lining, a^3 , provided with ribs a^4 , substantially as and for the purposes specified.

5 12. The tuyere B, located at the lower portion of the fire-chamber, and provided with raised portion b^2 and ledge b' , in combination

with a lining, a^3 , provided with ribs a^4 and interspaces, substantially as and for the purposes specified.

HIRAM W. RANSOM.
